UNITED STATES PATENT OFFICE

2,542,153

MEAT SLICING MACHINE

John McMillan, Coventry, England

Application April 7, 1947, Serial No. 739,911
In Great Britain November 7, 1945Section 1, Public Law 690, August 8, 1946
Patent expires November 7, 1965

3 Claims. (Cl. 146—102)

1

This invention relates to a meat or like comestible slicing machine of the kind having a rotatable knife (which may be manually or power-operated) operating in conjunction with a reciprocable table for supporting the bacon or other comestible to be sliced.

At the present time such machines are made of different sizes, common table sizes being 12" and 15", and this involves the use of different-sized bases from which the tables are to be supported, and, in particular, as regards the larger-sized table, the overall length of the base has to be somewhere in the neighbourhood of 30" for, say, an 18" stroke, unless use is made of outriggers for supporting the ends of guides for the table-supporting slide.

One of my objects is to provide improvements by means of which the overall size of the base can be reduced.

A further object is to provide a construction with which one type of base may be used for different-sized tables.

A further object is to provide, as a support for the table (particularly in the case of the larger-sized table), a slide having limited reciprocable movement with respect to a supporting slide which in turn has limited reciprocable movement with respect to the supporting base of the machine.

An application of the invention to a meat slicing machine, the table of which is to be reciprocated by alternately pushing and pulling by hand, is illustrated by way of example in the accompanying drawings, of which—

Figure 1 is a plan showing the means for supporting the table on the base, table, knife and knife guard being omitted for the sake of clearness;

Figure 2 is a section on the line 2—2 of Figure 1; and

Figure 3 is an elevation of the machine looking from the left of Figure 1, but showing also the table, knife and knife guard.

In my co-pending application No. 729,910, filed April 7, 1947, which has become abandoned, I show other parts of the slicing machine in which the present slides are incorporated, namely, the rotary knife and sharpening unit therefor.

In the present Figure 3 the table is indicated at 7, the rotatable knife at 8, and the knife guard, for the comestible being sliced, at 9, the guard being in a plane parallel to that of the knife edge but set back behind the knife edge dependently upon the desired thickness of the slices to be cut.

2

In the present drawings a hollow supporting slide 11 is mounted upon a base 12 of the machine in an ordinary manner, that is, by being provided with spaced bosses 13 at one edge having aligned holes to slidably receive a supporting bar 14 fixed in lugs 15 carried by the base. The other edge of the supporting slide has an outwardly-extending tongue 16 (which may be integral therewith, or secured thereto as by riveting) to work in the channel of a guide member 17 which is parallel to the supporting bar 14. As shown, the member 17 is spaced above the base by distance-pieces 18 and is held in position by screws 19 which also pass through the latter.

Instead, however, of mounting the table 7 directly on the supporting slide 11, as is the common practice at the present time, I mount from this supporting slide another slide 20, from which the table 7 is supported, having limited reciprocable movement with respect to the slide 11. Thus, the slide 11, which may be of trapezoidal shape in plan as shown, is in the form of a frame, the second or table slide 20 being substantially of triangular shape in plan and being mounted in the interior of the slide 11. The latter carries a rigid bar 21 (parallel to the supporting bar 14) extending through bearing openings in lugs 22 at the appropriate edge of the table slide 20, the other edge of the latter (the apex of the triangle) carrying a U-shaped part to engage the upper and lower faces of the adjacent straight portion 23 of the supporting slide 11. Conveniently, this U-shaped part comprises a lug 24 and a detachable locating plate 25.

I may mount a rubber or like buffer 26 at each end of the slide 11 (or on the opposite edges of the table slide 20) to lessen the impact blow between the two slides, and, if desired, I may combine therewith a leaf spring 27 further to deaden the shock. Similar buffers, not shown, may be provided in the ends of the channel of the member 17 for coaction with the tongue 16 of the slide 11.

The upper surface of the lug 24, it will be observed, is above the slide 20, and the latter has two bosses 28 which, together with the lug 24, provide a three-point support for the table 7, holes 29 (which may be tapped) being provided in the slide for securing the table in position.

In practice, as the table is reciprocated, the table and table slide 20 can move relatively to the supporting slide 11 for, say, a travel of five or more inches, and the table, the table slide,

and the supporting slide 11 can move in unison for a travel of, say, thirteen or less inches, as necessary, to give the desired overall table travel.

The length of the base of the machine is, of course, dependent inter alia upon the travel of the supporting slide 11 and, in consequence, for a slicing machine adapted to have a 15" table, the overall length of the base is reduced as regards normal strokes, or, conversely, the use of outriggers for supporting the bar or other guide for the usual slide is obviated. When, however, I wish to supply a slicing machine with, say, a 12" table, I may use the same base as that for the 15" table and, in effect, mount the table directly on the supporting slide 11, using some or all of the screw holes 30 for the purpose. In this case the slide 20 is omitted.

What I claim as my invention and desire to secure by Letters Patent of the United States is:

1. For a comestible slicing machine of the kind including a rotatable knife operating in conjunction with a reciprocable table for supporting the comestible to be sliced, a supporting base providing spaced parallel guides extending longitudinally of the machine, a hollow slide of trapezoidal shape supported by said guides, and a hollow table slide of triangle-like shape supported and guided by the parallel sides of said trapezoidal slide for movement parallel to said parallel guides, whereby the total reciprocal movement of said table slide is shared by said two slides, said table slide providing the first part of the reciprocal movement in each direction and said trapezoidal slide the second part when said table slide reaches the end of its travel with respect to said trapezoidal slide.

2. A slicing machine including a stationary

base, a pair of spaced parallel guides supported thereby, a hollow slide supported by said guides said slide having two spaced guides parallel to said guides first-mentioned, and a triangular table slide having one side supported by one of said second-mentioned guides and the point of the triangle opposite said one side supported by the other of said second-mentioned guides, said triangular slide being disposed mainly in the hollow of said first-mentioned slide.

5 3. A slicing machine according to claim 2, characterised in that said first-mentioned slide is of trapezoidal shape, its two non-parallel sides being substantially parallel respectively to the 10 adjacent sides of said triangular slide which are 15 connected to the ends of said one side thereof.

JOHN McMILLAN.
